MACHINE FOR BEVELING OARS

Harry Ronquist, Ketchikan, Territory of Alaska

Application November 14, 1941, Serial No. 419,213

5 Claims. (Cl. 144—144)

My invention relates to improvements in machines for beveling oar blades, the principal object in view being to provide a simply constructed automatic machine for beveling the sides of said blades, quickly, accurately and smoothly to the shank of the oar, and which is economical to manufacture, install and service, and adapted to form any shape and size blade.

To the accomplishment of the above and subordinate objects presently appearing, a preferred embodiment of my invention has been illustrated in the accompanying drawings, set forth in detail in the succeeding description, and defined in the claims appended hereto.

In said drawings:

Figure 1 is a view in top plan of the preferred embodiment of my invention.

Figure 2 is a view partly in longitudinal section and partly in side elevation.

Figure 3 is a view in vertical transverse section taken on the line 3—3 of Figure 2.

Figure 4 is a fragmentary view in vertical section taken on the line 4—4 of Figure 2 and drawn to an enlarged scale.

Figure 5 is a view in vertical section taken on the line 5—5 of Figure 4.

Figure 6 is a view in vertical section taken on the line 6—6 of Figure 2.

Figure 7 is a view in vertical section taken on the line 7—7 of Figure 2 and drawn to an enlarged scale.

Figure 8 is a detail view in bottom plan of the side clamps, and

Figure 9 is a fragmentary view in top plan of the carriage tracks and the rack and pinion drive.

Fig. 10 is a view in vertical transverse section taken on line 10—10 of Fig. 2.

Referring now to the drawings by numerals, as illustrated, the operating parts of my improved machine are mounted on an elongated frame structure including a pair of post-like legs 1 spaced apart transversely at the front end of the frame, a single, similar leg 2 at the rear end of said frame, and an intermediate pair of similar legs 3 spaced similarly to legs 1 and located substantially mid-way between the legs 1 and 2.

Vertically adjustable means for supporting an oar in horizontal position is provided as follows: Intermediate the pairs of legs 1, 3 is a pair of horizontally disposed, laterally spaced bars 4 arranged upon opposite sides of the longitudinal center of the frame, respectively. Each bar 4 is supported by a pair of subjacent, eccentric

10 housings 5 secured to the under side thereof adjacent opposite ends of the bar and which are bolted thereto, as at 6, the housings 5 at corresponding ends of the bars 4 being arranged in 5 opposed pairs aligned transversely of the frame and spaced apart in each pair. The sides of the housings 5 are vertically slotted, as at 7, and each housing is provided with an open bottom closed by a cap plate 8 bolted to the housing as at 9, see Figure 5. Extending from what constitutes the rear ends of the pair of bars 4, in the longitudinal center of the frame, and having one end mortised, as at 10, into said bars 4, and suitably secured thereto, is a single bar 11 having suitably fixed to its other end an eccentric housing 12 similar to housings 5 and which is disposed between a pair of bearing plates 13 arising from the top of the leg 2 and bolted thereto as at 14.

15 The described bars 4, 11 form, as will presently more clearly appear, an oar-supporting structure disposed intermediate the upper and lower ends of the pairs of legs 1, 3 and between the legs of said pairs.

20 For vertically adjusting the bars 4, 11, means

25 are provided comprising a pair of transverse rock shafts 15, 16 extending through the opposed pairs of eccentric housings 5, respectively, by way of the slots 7 therein, and a similar shaft 17 similarly extended through the eccentric housing 12, said shafts having eccentrics 18 fast thereon

30 The shafts 15, 16 are journaled at their ends in pairs of bearing brackets 19, 20, respectively, extending horizontally from the pairs of legs 1, 3, respectively, and suitably bolted thereto as at 21. Crank arms 22, 23, 24 depend from the shafts 15,

35 16, 17, respectively, with one end fast thereon. Links 25, 26 suitably pivoted to the other ends of said crank arms 22, 23, 24 connect the latter together for operation in unison. Fast on one end of the shaft 16, which as will be seen is arranged adjacent the rear ends of the bars 4, is an upstanding arm 27 for operating the shaft 16, and consequently through the crank arms 22, 23,

40 24 and links 25, 26, operating the shafts 15, 17 in the proper direction to elevate the bars 4, 11.

45 A pair of end clamps 28, 29 are provided on the bars 4 and the bar 11, respectively, for mounting an oar A on the same to extend lengthwise in the longitudinal center of the machine, blade end foremost and over the bars 4. The front clamp 28 comprises a suitable plate-like member

30 adapted to bear against the front end of the oar A and which is slidably mounted on the bars 4 for adjustment along the same into different set positions as established by a suitably arranged hand screw 31 threaded into the clamp. The rear clamp 29 comprises a sleeve 32 slidably mounted on the bar 11 for adjustment in the same manner as clamp 28 into positions established by hand screws 33, said sleeve having a forwardly extending pin 34 thereon adapted to extend into the rear hand grip end of the shank of the oar A.

A pair of side clamps for engaging the blade of the oar A upon opposite sides thereof is mounted in opposed relation in the bars 4, respectively. Each side clamp comprises a head 35 fixed eccentrically on the upper end of a spindle 36 journaled in the bar 4 in upright position and having a crank arm 37 fast on its lower end, the arrangement being such that under swinging of the crank arm in opposite directions, the head 35 will be rotated into and from frictional clamping relation to the blade of the oar A. The hand lever 38 pivoted, as at 39, on the bar 11 is operatively connected to the crank arms 37 by a rod 40, so that by operation of said lever in opposite directions said heads 35 may be rotated into and from clamping relation with respect to opposite sides of the blade of the oar A to hold the said blade standing on edge and to center the same in the longitudinal center of the machine. At the rear ends of the bars 4 is another clamp for engaging opposite sides of the shank of the oar A in the rear of the blade, this clamp comprising a fixed jaw plate 41 upstanding from one bar 4, and an opposed movable jaw plate 42 suitably mounted on a hand screw 43 threaded into the plate 41 for turning to move the plate 42 toward and from clamping relation to the plate 41.

For beveling the blade of the oar A, a pair of opposed, rotary, cylinder-like cutters 44 are provided upon opposite sides of the longitudinal center of the machine, said cutters converging axially upwardly to impart the usual bevel to said blade from the longitudinal center of the latter to whichever edge of said blade is arranged uppermost. For reasons presently seen, the cutters 44 are mounted in a pair of suitable bearings 45 which are swingably suspended from an overhead carriage 46 so that said bearings 45, and cutters 44, may pivot laterally to vary the degree of bevel cut thereby. The mountings for the bearings 45 comprise trunnions 47, the axes of which extend lengthwise of the machine, and bearing ears 48 depending from said carriage. The cutters 44 are fast upon the upper ends of a pair of cutter driving shafts 49 converging upwardly upon opposite sides of the longitudinal center of the machine and suitably journaled at their upper ends in bearings 45. The cutter driving shafts 49 are connected at lower ends, by friction clutches 50, to the upper ends of a pair of armature shafts 51 of a pair of cutter operating motors 52, said armature shafts being axially aligned with the cutter driving shafts 49, as will be understood. A pair of motor supporting frames 53 are suspended from the trunnions 47 to swing about the axes of the latter so that the motors 52 may swing laterally. A pair of grooved rollers 54 rotatably mounted on the lower ends of the armature shafts 51, respectively, ride on a pair of track rails 55 extending horizontally, lengthwise of the machine upon opposite sides of said longitudinal center of the latter. The track rails 55 curve laterally outwardly, rearwardly in diverging relation for a purpose presently seen

and the ends thereof are journaled in bearings 56 bolted, as at 57, to a pair of cross-bars 58 which, in turn, are bolted, as at 59, to the pairs of legs 1, 3, respectively.

The carriage 46 comprises a rectangular plate 60, corner pairs of laterally spaced hangers 61 upstanding from said plate, and concave rollers 62 journaled between the hangers 61 of said pairs and running upon a pair of parallel, laterally spaced tracks 63 extending lengthwise upon opposite sides of the longitudinal center of the machine above the carriage 60 with the ends thereof of suitably fixed, by plates 64 bolted to cross-bar 65 extending between the pairs of legs 1, 3.

Surmounting the plate 60 of the carriage 46 is a reversible carriage propelling motor 66 connected by a belt and pulley drive 67 to a transmission, designated 68, fixed on the carriage plate 60 and including a driving gear pinion 69 meshing with a rack bar 70 extending along the side of and fixed to one of the tracks 63.

A suitable reversing switch 71 is fixed to one of the legs 3 and operatively connected by any suitable wiring, not shown, in circuit with the motor 66 to reverse the same. A link 72 operatively connects the beforementioned arm 27 to said switch 71, the arrangement being such that when the arm 27 is operated to cause elevation of the bars 4, 11 and the oar A, in the manner already described, said arm 27 will, through the operating connection 72, operate the switch 71.

The tracks 63 and the rack 70 are provided adjacent their rear ends with a downwardly curved stretch, 74, in the track, and 75 in the rack 70, and for a purpose presently described.

Referring now to the operation, an oar A with the shank formed and the blade blocked out in the rough and in the form of an elongated rectangle is secured in place on the described oar supporting structure, i. e., the bars 4 and 11, with the blade standing on edge and secured in place by means of the described front and rear clamps 28, 29, the eccentric heads 35 of the described side clamps, and the clamps 41, 42, the blade of the oar A being arranged lengthwise so that its rear end, or in other words its juncture with the shank, is below the downwardly curved stretches 74 of tracks 63 and the corresponding stretch 75 of the rack 70. The cutters 44, cutter carriage 46, and parts carried by the latter should be previously set forwardly of the blade of the oar A either by operation of the motor 66 under control of any appropriate switch, not shown, or manually.

The motor 66 is next started to drive the carriage 46 and parts carried thereby rearwardly on the tracks 63 and the cutter operating motors 62 are started by means of any suitable control, not shown, to drive the cutters in reverse direction, relatively, to effect cutting thereby. As the carriage 46 travels rearwardly, the cutters 44 bevel the uppermost longitudinal half of the blade of the oar A. As said cutters 44 approach the juncture of the blade with the shank of the oar A, the rearmost rollers 62 enter the curved stretches 74 of track 63 and cause the carriage 46 to tilt rearwardly and downwardly and thereby lower the cutters 44 so that the blade is rounded off along its upper edge and said edge merged into the shank of the oar A in the usual manner. As the carriage 46 travels rearwardly, the outwardly and rearwardly curved, divergent tracks 55 cause the rollers 58 riding along the same to swing outwardly thereby, in a manner which will 75 be clear, swinging the cutter driving motors 57

outwardly, and the shafts 51, 49 and cutters 44 to vary the angle of convergence of said cutters so that the blade of the oar A above its longitudinal center is gradually cut thicker and its upper edge is cut or formed on an incline toward the shank, as is usual. As the rearmost rollers 62 of the carriage 46 start to ride up the stretches 74, said carriage engages the beforementioned arm 27 and operates the same to operate the described mechanism for elevating the oar-supporting structure, i. e., the bars 4, 11, said arm 27 being moved rearwardly in this operation and operating the reversing switch 71 to cause the carriage driving motor 66 to reverse. The elevation of the oar-supporting structure positions the oar A for further beveling under return travel of the carriage 46 and operation of the cutters 44 in a manner which will be clear. The described eccentrics 18 frictionally engage the tops of the housings 5, 12 and interlock therewith to thereby hold the oar-supporting structure elevated and the arm 27 in a rearward position. At the limit of forward, reverse travel of the carriage 46 and the cutters 44, the links 27 may be operated manually to lower the oar-supporting structure and return the arm 27 from switch operating position. The tracks 55 being journaled, as described, are free to swing vertically under engagement of the rollers 54 therewith and thereby compensate for outward swinging and inward swinging of the motors 52 and parts driven by the latter. The function of the curved stretch 75 of the rack 74 is to maintain the described carriage drive in operation during tilting of the carriage.

In actual practice the described machine has been found highly efficient in turning out oars rapidly and of uniform design, relatively, and at approximately the rate of one a minute.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the subjoined claims.

What I claim is:

1. In a machine of the class described, a horizontally disposed elongated oar supporting structure, means to secure an oar thereon in horizontal position with the blade of the oar standing on edge, and oar beveling mechanism constructed and arranged to travel along opposite sides of said blade, and means to adjust said supporting structure vertically under travel of said mechanism comprising rotary cams spaced apart longitudinally of said structure and supporting the same, an arm operatively connected to one cam for swinging movement to rotate the cam and interposed in the path of travel of said mechanism, and devices connecting said cams for rotation in unison.

2. In a machine of the class described, a horizontally disposed oar supporting structure, means

5 to secure an oar thereon in horizontal position with the blade of the oar standing on edge, and oar beveling mechanism constructed and arranged to travel along opposite sides of said blade, said mechanism comprising a pair of opposed cutters rotatable about axes upwardly converging relatively, a pair of motors below said cutters having armature shafts extending therethrough in upright position and axial alignment 10 with said cutters, respectively, operating connections between the upper ends of said armature shafts and said cutters, respectively, a pair of horizontal tracks, and a pair of grooved rollers on the lower ends of said armature shafts running 15 on said tracks, respectively.

3. In a machine of the class described, a horizontally disposed oar supporting structure, means to secure an oar thereon in horizontal position with the blade of the oar standing on edge, and 20 oar beveling mechanism constructed and arranged to travel along opposite sides of said blade, said mechanism comprising a pair of opposed cutters rotatable about axes upwardly converging relatively, and swingable about horizontal axes to vary the angle of convergence thereof, a pair of operating shafts depending from said cutters, respectively, axially thereof, a pair of horizontal tracks flaring laterally, relatively, and a pair of grooved rollers on the lower ends of said 25 shafts running on said tracks whereby the cutters are swung by said shafts as an incident to travel of said mechanism and to thereby vary the angle of convergence of the cutters.

4. In a machine of the class described, a horizontally disposed oar supporting structure, means to secure an oar on said structure in horizontal position with the blade standing on edge, tracks 35 above said structure extending lengthwise longitudinally thereof, a carriage traveling along said 40 tracks, a pair of rotary motor operated cutters suspended from said carriage for travel along opposite sides of said blade under travel of the carriage, a motor drive for said carriage, said cutters being rotatable about axes converging relatively, 45 and means to vary the converging relation of said axes as an incident to travel of said carriage, said tracks having downwardly bowed bends therein for lowering said carriage to correspondingly lower said cutters and cause the cutters to 50 round off the blade at one end thereof.

5. In a machine of the class described, a horizontally disposed oar blade supporting structure vertically adjustable, tracks above said structure extending lengthwise longitudinally thereof, a 55 motor driven carriage traveling along said tracks in opposite directions, respectively, between opposite limits of movement, a pair of rotary cutters suspended from said carriage to travel along opposite sides of said blade under travel of the carriage, and carriage operated means for adjusting said structure in one limit of movement of said carriage, and a switch for reversing said motor operated by said carriage in said limit of movement thereof.

HARRY RONQUIST.
